ORNAMENTAL CROSS STRUCTURE

Raymond F. Brennan, Attleboro, Mass.

Application July 15, 1940, Serial No. 345,559

4 Claims. (Cl. 41—35)

This invention relates to an ornamental cross structure, and more particularly to a device of this character provided with recessed faces formed in the upright and transverse arm sections having thin strips of ornamental material mounted therein to provide ornamentation for the cross surfaces.

Another object of the invention is the provision of thin strips of uniform thickness formed from an ornamental material and shaped to fit slidably within recessed faces formed in portions of the upright and transverse arm sections of the cross.

A further object of the invention is the provision in a device of this character of recessed faces containing ornamental strips and having ornamental inserts adapted to be positioned in portions of the recessed faces formed in the upright and transverse sections of the cross for holding the ornamental strips in position and providing additional ornamental features in the appearance of the cross.

Other objects and advantages of the invention relate to various improved details of construction and novel arrangements of the parts as will be more fully set forth in the detailed description to follow.

Referring to the drawing:

Fig. 1 is a perspective view of a cross showing the upright and arm sections provided with recessed areas containing ornamental material in the form of strips located in opposed grooves formed in the body of the cross and illustrating one of the ornamental strips in partially extended position.

Fig. 2 is an enlarged transverse sectional view of a portion of the upright or transverse arm section, taken as indicated along one of the lines 2—2 shown in Fig. 1.

Fig. 3 is a front elevational view of a cross structure, parts being broken away, showing ornamental strips mounted in recessed face areas with ornamental inserts located adjacent to the ends of the strips and positioned within the recesses serving as further ornamentation and holding means for the strips, and,

Fig. 4 is an enlarged transverse sectional view showing the structure as seen when viewed along the lines 4—4 of Fig. 3.

In the embodiment of the invention illustrated in Figs. 1 and 2 of the drawing, a cross 1 may comprise lower and upper upright sections 3 and 4 and transverse arm sections 5 and 6. The cross may be formed conveniently from wood, metal, plastic or other suitable material, and may be of integral construction throughout or formed from separate elements suitably fitted and secured together.

The ornamentation may be applied both to front and side faces of the upright and transverse

cross sections, or to any of them, but is shown herein as applied only to the front faces thereof. The upright and transverse cross sections are provided with recessed faces 10 which are to be overlaid by thin ornamental strips 11. The ornament receiving faces 10 may extend longitudinally of each upright and transverse arm section of the cross and the cross sections are provided with oppositely positioned raised lateral shoulders 12 projecting outwardly from each ornament receiving face portion. Each raised lateral shoulder is provided with a groove 14 formed in the face thereof adjacent to the ornament receiving face of the section; the grooves formed in oppositely positioned shoulders being located in opposed relation with each other to receive the opposite lateral edges 16 of a thin, ornamental strip 11 adapted to overlie the ornamental receiving face of the cross section.

20 The strips 11 may be formed of any suitable ornamental material, such as, ornamented or plain surfaced metal, plastic, ivory, pearl, celluloid, paper, fabric, or other desired material and formed of suitable width to extend across the 25 ornament receiving face of a section of the cross, and have their lateral edges 16 positioned within the opposed grooves 14. These strips may be slidably inserted from one end of each or certain cross sections to fit closely against the face portion thereof lying between the opposed lateral shoulders carried by that portion of the cross, and with the strip ends terminating at or adjacent to the ends of the opposed shoulders 12.

In the embodiment of the invention above described the ornament receiving faces of the transverse arms 5 and 6 lie in a common surface, as do the corresponding faces of the upright sections 3 and 4, and a single strip 11 may be employed either for the faces of the transverse 30 sections or for the faces of the upright sections, with separate strips 11 for the remaining sections shaped to engage closely with the lateral edges of the continuous strip in the assembled position of the strips.

45 The ornamental strip elements employed as applied to the upright and transverse arm sections of a cross may be similar in character to provide a uniform ornamental effect for each cross section, or the ornamental strips as applied to the upright and transverse cross sections may be of a different or contrasting appearance throughout all, or portions of their extent, to provide contrasting ornamental effects for different portions or parts of the cross sections.

50 In any case, it is regarded as preferable that the oppositely positioned grooves 14 formed in opposed shoulders 12 be located throughout in a common plane which is uniformly arranged with respect to that portion of the recessed face included therebetween and located closely adja-

cent to the side edges of each recessed face, so that each strip 11 may be located in proximity to or bear against the recessed face portion 10 covered thereby when in its display position.

The ornamental strips 11 may be inserted slidably from open ends of the grooves 14 terminating adjacent to one end of a cross section and forced inwardly throughout such section or into meeting engagement with a strip located in one or the other of the cross sections positioned at right angles relative thereto.

In that form of the invention shown in Figs. 3 and 4, the cross sections 3, 4, 5 and 6 are provided with recessed faces 10 to receive strips 11 as previously described, and raised lateral shoulders 12 are provided with opposed grooves 14 to receive lateral edges 16 of the strips 11 as in the form of the invention previously described.

In this form of the invention inserts 18 are provided which are adapted to be fitted into the outer ends of opposed grooves 14 over the ends 19 of the strips 11 to further contribute to the ornamental effect and at the same time provide holding means for securing the strips 11 firmly in position relative to the recessed faces of the cross sections.

The inserts 18 may be of any suitable ornamental character, formed of metal or other desired material and of such shape and size as to provide lateral edges 20 adapted to fit within 30 the opposed grooves 14 and to overlie the free ends 19 of the strips 11 for clamping the strips firmly in position and holding them securely against movement in directions longitudinally of their extent.

In either form of the invention shown, the raised lateral shoulders 12 having grooves 14 formed therein, and including the recessed face areas 10 of the cross sections, may constitute an integral part of each cross section or may be in the form of a separate plate secured in any suitable or desired manner to faces of the underlying cross sections. When such separate elements are employed to provide the lateral shoulders and recessed faces, such elements may be formed from similar material to that constituting the main or base portion of the cross sections or may be formed from a different material than that forming the base portions of the cross sections, as may be desired.

What I claim is:

1. A cross structure of the character described comprising opposite upright and transverse arm sections each provided upon one side with a longitudinally extending recessed face spaced inwardly from the plane of its lateral edges and continuous with the corresponding face of the opposite section, lateral shoulders carried by each said section extending outwardly of the recessed face and provided with opposed grooves formed in the opposite side faces thereof and located in proximity to the recessed face area, a thin strip of ornamental material of substantially uniform width throughout its extent having the lateral edges thereof interfitting within 55 the opposed grooves formed in the inner faces of oppositely positioned lateral shoulders and overlying the intermediate recessed face area, and ornamental inserts overlying the free ends of said ornamental strip adjacent to the free 60 ends of said arm sections and each having opposite lateral edges fitting within the opposed grooves at points adjacent to and outwardly of the free ends of the ornamental strip to pro-

vide an additional ornamental effect and hold said strip securely in position relative to said cross sections.

2. A cross structure of the character described comprising opposed, upright and transverse arm sections, which are provided upon one side with longitudinally extending recessed areas of substantially uniform width located between their corresponding lateral edges, aligned shoulders located adjacent to the lateral edges of opposed sections on opposite sides of said recessed areas and projecting outwardly from said areas, said shoulders being provided upon the inner faces thereof with oppositely positioned grooves located adjacent to the recessed areas formed in the sections, ornamental strips each of substantially uniform width throughout slidably mounted in the opposed grooves formed in said shoulders and having their central longitudinal areas located in proximity to said recessed areas, and means positioned within opposed grooves adjacent to the free ends of said arm sections and outwardly of said strips for holding the outwardly located free end portions of said ornamental strips securely in position relative to the arm sections.

3. A cross structure comprising oppositely positioned upright and transverse arm sections each having front faces the opposite free edges of which are provided with raised shoulders having opposed grooves formed therein, the shoulders of each upright and transverse arm section being located in substantial alignment with the corresponding shoulders of the opposite upright and transverse arm sections respectively to define recessed areas in the front faces of the oppositely positioned upright and transverse arm sections continuous throughout the extent of said sections, and ornamental strips each of substantially uniform width slidably mounted in the opposed grooves formed in the raised shoulders of said sections and located in proximity with the recessed areas formed therein, one of said strips extending throughout the entire lengths of opposed arm sections and transversely of the recessed area formed in the other arm sections.

4. A cross structure comprising oppositely positioned upright and transverse arm sections each having front faces the opposite free edges of which are provided with raised shoulders having opposed grooves formed therein, the shoulders of each upright and transverse arm section being located in substantial alignment with the corresponding shoulders of the opposite upright and transverse arm sections respectively to define recessed areas in the front faces of the oppositely positioned upright and transverse arm sections continuous throughout the extent of said sections, ornamental strips each of substantially uniform width slidably mounted in the opposed grooves formed in the raised shoulders of said sections and located in proximity with the recessed areas formed therein, one of said strips extending throughout the entire lengths of opposed arm sections and transversely of the recessed area formed in the other arm sections, and means engaging certain of said strip ends adjacent to the free ends of the arm sections and secured to the corresponding free ends of the arm sections to retain said strips in position relative to said arm sections.

RAYMOND F. BRENNAN.
